SAFETY RAZOR SET CASE

Charles L. Metzler, Palisades Park, N.J., and William H. Dennerlein, Bethpage, and Leon B. Bernstein, Hicksville, N.Y.

Application January 12, 1959, Serial No. 54,133

Term of patent 14 years

(Cl. D80—5)

Fig. 1 is a front elevational view of a safety razor set case embodying our new design;

Fig. 2 is a right side elevational view of the case, the left side being a mirror image thereof; and

Fig. 3 is a perspective view thereof with the cover in a removed position to show the interior of the case.

The back of the case is plain.

We claim:

The ornamental design for a safety razor set case, as shown and described.
